ROSARY BEAD

Christy M. Del Mas, New York, N. Y.

Application August 6, 1953, Serial No. 26,329

Term of patent 14 years

(Cl. D45—16)

To all whom it may concern:

Be it known that I, Christy M. Del Mas, a citizen of the United States of America, residing at city, county, and State of New York, have invented a new, original, and ornamental Design for a Rosary Bead, of which the following is a specification, reference being had to the accompanying drawing, forming part thereof.

omitting for convenience of illustration the ornamentation shown within the circular elements of Figures 1 and 2.

I claim:

The ornamental design for a rosary bead, as shown and described.

CHRISTY M. DEL MAS.
